UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed August 29, 1923. Serial No. 659,866.

The invention relates to draft gears for railway cars, of the type in which friction is developed between parts having a turning movement about the axis of the gear.

5 The objects of the invention are to secure high efficiency, simplicity of construction, and durability.

The invention consists in a structure such as is hereinafter described and illustrated 10 in the accompanying drawings, in which

Fig. 1 is a central plan section of the gear, details of parts of a car being shown in plan;

15 Fig. 2 is a similar view, the gear being compressed, some of its parts being shown in plan and portions being broken away to clearly show positions assumed by enclosed parts;

Fig. 3 is a detail section on the line 3—3 of Fig. 1;

20 Fig. 4 is a face view of a non-rotative element of the gear and of a spring element housed therein;

Fig. 5 is a face view of one of the rotative elements of the gear, showing the spring 25 pocket; and

Fig. 6 is an edge view of one of the rotative and one of the non-rotative elements of the gear, showing their relation in release position.

30 A pair of center or draft sills of a railway car are shown at 10, 10, each being provided with the usual draft lugs 11, 11, and buffing lugs 12, 12. The butt end of a coupler is represented at 13, and its extension, tail-strap or 35 yoke at 14.

The gear is inclosed within the yoke element 14, and comprises a pair of chambered followers 15, 16, for cooperating, respectively, with the draft and buffing lugs. The body or

40 shell 17 of each of the followers has a cylindrical bore, having, however, longitudinal recesses, preferably at the top and bottom, as shown at 18, 19, and is of such length that the bodies of the two followers meet to limit the 45 compressive movement of the gear.

The inner face of each of the followers is provided with an annular series of teeth, as 20, preferably formed integral therewith, each having an inclined face, as 21, serving 50 as an inclined plane or wedging surface.

Housed within the barrel of each follower is a series of non-rotative elements, as 22, 23, each being provided with an annular series 55 of teeth 24, 25, of the same form as the teeth 20. An elongated non-rotative element 26

fits within the adjacent ends of the shells of both followers. Each of the non-rotative elements 22, 23 and 26 is provided with lateral lugs 27, 28, which fit within the recesses 18, 19.

60 Interposed between the end walls of each follower and the non-rotative element 22, between the toothed face of the latter element and the smooth face of the element 23, and between the toothed face of the latter element and the end of the element 26, are rotative 65 rings 29, 30 and 31, each having an annular series of teeth complementary to and engageable with the teeth of the adjacent element.

Within the plane face of each of the rotative and non-rotative elements there is 70 formed a segmental channel 32, 33, of such length as to almost form a complete circle, these channels being so disposed that those of adjacent elements register. Inclosed within the registering channels of each pair of rotative and non-rotative elements is a segmental spring 34, the ends of which abut against the ends of the channels. The normal diameter of the segmental springs is 75 somewhat less than the maximum diameter of 80 the channels.

The elements 22, 23, 26, 29, 30 and 31 are 85 annular in form, providing an axial chamber from end to end of the gear within which there is housed a releasing spring 35, reacting between the end walls of the two followers.

The follower casings may be provided with apertured radial lugs, as 36, 37, for the accommodation of retaining bolts 38, which 90 serve to hold the gear parts in assembled relation during shipment and installation. These bolts may be removed when the gear is installed.

All of the rotative elements, as 29, and non-rotative elements, as 22, 26, are axially movable with reference to the follower casings. In release position of the gear the apexes of the teeth of the rotative elements are in engagement with the teeth of the non-rotative 95 elements near the apexes thereof. Axial movement of the enclosed parts implies the sliding of the teeth of the rotative elements down the inclined surfaces of the teeth of the non-rotative elements.

100 Movement of either of the followers under the influence of draft or buffing stresses causes a turning movement of the rotative element, as 29, associated therewith, by the wedging action of the interengaged teeth of 105 110

these two parts. This turning movement is resisted by the spring 34, one end of which is carried along by the shoulder constituting the end of the channel 32 in the rotative element, while the other end thereof is held by the shoulder constituting one end of the channel 33 in the non-rotative element, thus causing an expansion of the spring. Turning movement is also resisted by the friction between the rear or plane faces of the rotative and non-rotative elements; and by making the springs 34 of the same width as the combined depth of the channels 32 and 33 resisting friction is developed between the sides of the springs and the bottom walls of the channels. In practice the engaging surfaces of the rotative and non-rotative elements will soon wear away sufficiently to cause this frictional action of the springs. Indeed it is believed that this friction will be sufficient to cause the expansion of the springs if the end walls of the channels of one of the elements were absent, though better practice calls for them.

In like manner all of the remaining rotative elements are given a turning movement by the wedging action of their teeth in co-operation with the teeth of the non-rotative elements, and the several springs associated with these parts are similarly expanded. The axial spring 35 is also compressed by the advance movement of either of the followers.

Compressive force applied to the gear is, therefore, absorbed by the spring 35, the several springs 34 and the friction developed between the teeth of the rotative and non-rotative elements, and between the meeting plane faces of these parts.

The various parts are so proportioned that the ends of the follower casings engage, as shown in Fig. 2, as the various wedging teeth approach the limit of their respective movements and the springs 34 approach the limit of expansion determined by the diameter of the channels 32, 33.

Upon the relief of the compressive force all of the springs cooperate to effect the release of the gear and the return of all of its parts to the normal position, as shown in Fig. 1.

The improved gear is cheap of construction, as no machining of the parts is necessary.

While a preferred and highly efficient embodiment of the invention is disclosed, various changes in the form and arrangement of parts may be made within its scope.

I claim as my invention—

1. In a draft gear, in combination, a chambered follower, an annular series of inclined surfaces within the chamber and formed on a transverse wall thereof, a rotative element having a complementary series of inclined surfaces, spring means opposing turning movement of the rotative element, and means resisting axial movement of such element.

2. In a draft gear, in combination, a pair

of chambered followers, pairs of wedging elements housed within each follower, the members of each pair having cooperating wedging teeth arranged annularly, one member of each pair being non-rotative and the other member being free to turn, and segmental springs located between adjacent pairs of wedging elements and reacting between abutments carried by the two elements.

3. In a draft gear, in combination, a chambered follower, a rotative element housed within the follower and having an annular series of wedging teeth, a set of wedging teeth cooperating with the first-named set of teeth and carried by a non-rotative part, and a segmental spring between a shoulder on the rotative element and a relatively fixed abutment.

4. In a draft gear, in combination, a chambered follower, a plurality of rotative elements housed within the follower and having on one face an annular series of wedging teeth; non-rotative elements having complementary wedging teeth cooperating with each set of the first-named teeth, and segmental springs seated in segmental channels in each rotative element and similar channels in an adjacent non-rotative element.

5. In a draft gear, in combination, a pair of chambered followers each having an annular series of wedging teeth on the inner face of its end wall, a plurality of rotative axially movable elements each having an annular series of wedging teeth on its side facing the adjacent end of the gear, non-rotative axially movable annular elements interposed between the rotative elements and having wedging teeth complementary thereto, a central non-rotative axially movable element located within the chambers of both followers, and segmental springs housed within segmental channels in the untoothed face of each rotative element and the adjacent face of a non-rotative element.

6. In a draft gear, in combination, a pair of chambered followers each having an annular series of wedging teeth on the inner face of its end wall, a plurality of rotative axially movable elements each having an annular series of wedging teeth on its side facing the adjacent end of the gear, non-rotative axially movable annular elements interposed between the rotative elements and having wedging teeth complementary thereto, a central non-rotative axially movable element located within the chambers of both followers, segmental springs housed within segmental channels in the untoothed face of each rotative element and the adjacent face of a non-rotative element, and a spring located on the axis of the gear and between the two followers.

7. In a draft gear, in combination, opposed followers, two sets of annularly arranged co-operating wedges, formed respectively on disk faces of a rotative and non-rotative ele-

ment of the gear, interposed between the followers and capable of longitudinal movement relatively thereto, and friction means for resisting turning movement of the rotative element.

8. In a draft gear, in combination, opposed followers, two sets of annularly arranged cooperating wedges, formed respectively on a rotative and non-rotative element of the gear, interposed between the followers and capable of longitudinal movement relatively thereto, and friction and spring means for resisting turning movement of the rotative element.

9. In a draft gear, in combination, a chambered follower, a rotative element within the chamber having an annular series of wedges faces formed on its radial face, a complementary series of wedges cooperating with the first named series and secured against rotative movement, spring means for opposing turning movement of the rotative element, and means for resisting axial movement of such element.

10. In a draft gear, in combination, a pair of chambered followers, pairs of disk shaped elements housed within each follower, the members of each pair having cooperating wedging teeth arranged annularly, one member of each pair being non-rotative and the other member being free to turn, and spring means reacting between such members for resisting their relative turning movement.

11. In a draft gear, in combination, a pair of opposed followers, a pair of elements in-

terposed between the followers and having 35 contacting faces transverse to the axis of the gear, such faces being provided with cooperating annularly arranged series of wedges, one of such elements being rotative and the other being non-rotative, spring means 40 opposing the turning movement of the rotative element, and means opposing axial movement of said elements.

12. In a draft gear, in combination, a pair of opposed followers, a pair of relatively 45 rotatable disk shaped elements located between the followers, the contiguous faces of such elements being provided with annularly disposed cooperating wedges, means for opposing the relative turning movement of the 50 disk elements, and means resisting the axial movement thereof.

13. In a draft gear, in combination, a pair of chambered followers, a plurality of frictionally engaged annular elements housed 55 within each follower, adjacent elements being relatively revoluble, alternate pairs of contacting faces of such elements being respectively plain and provided with cooperating annularly arranged series of wedges, springs 60 reacting between adjacent elements for resisting the relative turning movement thereof, an annular cylindrical element interposed between the two sets of the first named elements and being housed within both followers, and a spring on the axis of the gear reacting between the followers.
